CLAIM

The ornamental design for a neck phototherapy device, as
shown and described.

DESCRIPTION

FIG. 1 is a perspective view of a neck phototherapy device
showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1.
The dash-dash broken lines in the drawings depict portions
of the neck phototherapy device that form no part of the
claimed design. The dot-dash broken lines represent bound-
aries of the enlarged portion that form no part of the claimed
design.
